HEATER FOR AQUARIUM WATER

Walter Sesholtz, Park Ridge, N.J., assignor to Sternco Industries, Inc., Harrison, N.J., a corporation of New Jersey

Filed Sept. 27, 1968, Ser. No. 13,749

Term of patent 14 years

Int. Cl. D23—03

U.S. Cl. D23—87

FIG. 2

FIG. 3

FIG. 6

FIG. 4

FIG. 5

FIG. 1 is a top perspective view of a heater for aquarium water showing my new design.

FIG. 2 is a front view in reduced scale thereof.

FIG. 3 is a rear view in reduced scale thereof.

FIG. 4 is a side view in reduced scale thereof.

FIG. 5 is an opposite view in reduced scale thereof.

FIG. 6 is a bottom view thereof.

The dominant features of my design reside in the portions shown in full lines.

The broken lines representing a fragmentary portion of an aquarium are shown for illustrative purposes only.

I claim:

The ornamental design for a heater for aquarium water, as shown and described.
